(57) **CLAIM**

The ornamental design for a tripod with wireless phone charger, as shown.

DESCRIPTION

FIG. 1 is a front perspective view of a tripod with wireless phone charger showing my new design.

FIG. 2 is a top plan view of the invention shown in FIG. 1. FIG. 3 is a left side elevational view of the invention shown in FIG. 1.

FIG. 4 is a bottom plan view of the invention shown in FIG. 1.

FIG. 5 is a front elevational view of the invention shown in FIG. 1.

FIG. 6 is a rear elevational view of the invention shown in FIG. 1.

FIG. 7 is a right side elevational view of the invention shown in FIG. 1.

FIG. 8 is a front perspective view of a second embodiment of a tripod with wireless phone charger showing my new design.

FIG. 9 is a top plan view of the invention shown in FIG. 8. FIG. 10 is a left side elevational view of the invention shown in FIG. 8.

FIG. 11 is a bottom plan view of the invention shown in FIG. 8.

FIG. 12 is a front elevational view of the invention shown in FIG. 8.

FIG. 13 is a rear elevational view of the invention shown in FIG. 8; and,

FIG. 14 is a right side elevational view of the invention shown in FIG. 8.
